PACKAGING MACHINE

Michael J. Kratoville, St. Louis, Mo.

Application January 17, 1949, Serial No. 71,360

4 Claims. (Cl. 226—14)

1

This invention relates to certain new and useful improvements in a packaging machine, and for illustration of the invention, a bottle packer is shown and described wherein bottle beverage is intermittently fed into the machine in grouped rows of six bottles each, from a conventional type of conveyor for depositing the bottles in four grouped rows into a package, carton or box, and the package when filled with a total of twenty-four bottles, being automatically discharged from the machine in readiness for inserting an empty package, carton or box into the machine for continuing packaging operations.

With the above in view, it is a primary object of the invention to utilize the moving force of the traveling bottle row of bottles on a conveyor to intermittently load grouped rows of bottles into the packaging machine, and to further intermittently move the assembled grouped bottle rows to positions ready for simultaneous deposit in the package or carton, by gravity actuated means.

Another object of the invention is to provide the machine with improved means for releasing the assembled grouped bottle rows to cause them to fall by gravity into the package or carton for simultaneously filling it, and whereby their falling weight will discharge the filled or bottle loaded carton from the machine and simultaneously elevate the counterbalancing weight of the gravity actuating means of the machine.

A further object is to provide a machine which automatically packs bottles in cartons and the like, as the cartons are separately fed into the machine, without any outside power agency other than the traveling force on the bottles as they are conveyor fed into the machine, in combination with gravity actuated devices which comprise parts of the machine.

With the foregoing and other objects in view which will appear as the description proceeds, my invention resides in the combination and arrangements of parts and in the details of construction hereinafter described and claimed, it being understood that changes may be made within the scope of what is claimed, without departing from the spirit and intents of the invention.

An embodiment of the invention is illustrated in the accompanying drawings wherein:

Figure 1 is an end elevation of this improved packaging machine showing a portion of a bottle conveyor in connection therewith.

Figure 2 is an elevation of the bottle feeding side of the machine, taken in the direction of the arrow 2 of Fig. 1.

Figure 3 is an elevation of the opposite side of Fig. 2 taken in the direction of the arrow 3 of Fig. 1.

Figure 4 is an enlarged fragmentary vertical sectional elevation of a portion of Fig. 3, taken on the line 4—4 of Fig. 1, as relating to the bottle

2

row groups as they are fed into the machine for arranging them into packed rows in readiness for gravity deposit into a carton or box.

Figure 5 is an enlarged fragmentary transverse vertical section taken approximately on the line 5—5 of Fig. 4.

Figure 6 is an enlarged fragmentary transverse vertical section taken approximately on the line 6—6 of Fig. 4 having an intermediate portion broken away.

Figure 7 is an enlarged fragmentary horizontal section taken approximately on the line 7—7 of Fig. 6.

Figure 8 is an enlarged fragmentary sectional elevation of one of the trap-door releasing levers shown in Fig. 6, in a locked position.

Figure 9 is an enlarged fragmentary side elevation of a portion of the upper part of Fig. 3 relating to the mechanism for pushing the bottle row groups in packed rows into the bottle loading compartment. Fig. 9 also has relation to the structure of Fig. 4.

Figure 10 is an enlarged fragmentary top elevation partly in section, of Fig. 9.

Figure 11 is an enlarged fragmentary transverse vertical section taken approximately on the line 11—11 of Fig. 9.

Figure 12 is an enlarged fragmentary transverse vertical section taken approximately on the line 12—12 of Fig. 10.

Figure 13 is an enlarged fragmentary vertical section taken approximately on the line 13—13 of Fig. 11.

Figure 14 is an enlarged fragmentary end elevation of certain of the gravity actuating mechanism, taken in the direction indicated by line 14—14 of Fig. 2.

Figure 15 is an enlarged transverse vertical section taken approximately on the line 15—15 of Fig. 14.

Figure 16 is an enlarged transverse vertical section taken approximately on the line 16—16 of Fig. 14.

Figure 17 is an enlarged fragmentary side elevation partly in section of part of the mechanism shown in the upper part of Fig. 2, for preventing bottles entering the machine to avoid jamming thereof, until a preceding grouped bottle row has been pushed from the bottle receiving slide into the loading compartment.

Figure 18 is an enlarged fragmentary vertical section taken approximately on the line 18—18 of Fig. 17.

Figure 19 is an enlarged fragmentary vertical section taken approximately on the line 19—19 of Fig. 18.

Figure 20 is an enlarged fragmentary horizontal section taken approximately on the line 20—20 of Fig. 18.

Figure 21 is an enlarged fragmentary vertical

sectional elevation taken approximately on the line 21—21 of Fig. 1.

Figure 22 is an enlarged fragmentary vertical sectional elevation taken approximately on the line 22—22 of Fig. 21.

Figure 23 is an enlarged fragmentary vertical sectional elevation taken approximately on the line 23—23 of Fig. 21.

Figure 24 is an enlarged fragmentary vertical sectional elevation taken approximately on the line 24—24 of Fig. 22.

Figure 25 is an enlarged fragmentary detail of the looped end of the windlass weight winding tape, and particularly relates to Figs. 1, 2, 21 and 23.

Figure 26 is an enlarged fragmentary vertical sectional elevation taken approximately on the line 26—26 of Fig. 1.

Figure 27 is an enlarged fragmentary vertical elevation taken approximately on the line 27—27 of Fig. 1.

Referring by numerals to the accompanying drawings 30 designates the frame of the packaging machine or packer which supports a bottle loading compartment 31 which is located adjacent the upper end of the frame, and disposed on one side of said compartment is a horizontal slide 32 having communication at one end with a bottle conveyor 33 leading from a bottling machine or the like, not shown. (Figs. 1, 2, 3 and 4.)

Longitudinal partitions 34 are disposed in the compartment 31 (Fig. 5) for providing six bottle stalls 35 therein for receiving bottle row groups of six bottles each as they are intermittently pushed from the slide 32 by the pusher plate 36. (Figs. 2, 3, 4, and 9.)

Each stall 35 is of a length to contain four upstanding bottles and each having a longitudinal trap-door 37 as a bottom wall therefor in horizontal alignment with the slide 32, and disposed beneath the compartment 31 and the trap-doors 37 thereof, is a grill 38 having a plurality of depending leaf springs 39 for relieving the falling weight of the bottles as they are released by the trap-doors after the compartment 31 has been filled with twenty-four bottles by four intermittent pushing operations of the pusher plate 36. (Fig. 1, 2, 3, 4 and 5.)

For receiving the falling bottles from the compartment 31, a carton A is secured directly beneath the grill 38 by a holder 40, said carton being placed in bottle receiving position by a carton rack 41, which is vertically slidable in the frame 30 by operation of a counterbalanced bar 42 which is pivotally mounted at 43, said carton rack being connected to the bar 42 by a link 44, the opposite end of said bar having a weight 45 thereon for counterbalancing the descending bottle filled carton A and the carton rack 41.

The counterbalanced bar 42 in addition to elevating the carton for security with the holder 40 and permitting lowering of the bottle filled carton also causes the filled carton to be engaged by mechanism for discharging the carton from the carton rack, upon said rack being lowered, to a position whereby the lowering weight of the filled carton will engage a pair of rollers 46 of a discharging element 47 which will project through the open-work of the rack when the rack has reached a lowered position such as shown in Fig. 1, said rollers 46 being pressed downward by the weight of the filled carton thereby causing the rollers 48 of the element 47 to engage and

push against a side wall of the carton for discharging it from the rack.

During lowering of the bottle filled carton A a pin 49 projected from a horizontally inclined shaft 50 is normally engaged in the looped end 51 of a metal strap 52 for engaging the lower end 53 of said looped end (Fig. 25), and inasmuch as the ends of the shaft 50 are supported in respective bearings 54 and 55, carried by the counterbalanced bar 42 (Fig. 21), the descending end of said bar will exert a downward pull on the strap 52, and as said strap is secured on its upper end at 56 to the periphery of a drum 57 forming part of a windlass 58 mounted on a shaft 59, said strap 52 will consequently be unwound from the drum 57 thereby turning it and at the same time a cable 60 which is secured to the periphery of the drum 61 of the windlass 58 (Figs. 2, 3, 14 and 15), will elevate the weight 62 which is fastened to the depending end of said cable thereby positioning the weight 62 in readiness for operating the windlass 58 for cooperation with mechanisms relating to the next loading of bottles into the compartment 31 from the conveyor 33 hereinafter described.

The pusher plate 36 is fastened to one end of a horizontally extending member 63 which is secured to a horizontal cross member 64 of a pair of vertical members 65 which are each pivotally secured at their lower ends at 66 to the frame 30, said parts 63 to 66 inclusive providing a swingable frame 67 to which a trip-lever support 68 is secured at the upper end thereof, said support bearing the trip-levers numbered 69, 70, 71 and 72, for cooperation with respective pusher arms 73, 74, 75 and 76 which are radially extended from the drum 57 of the windlass 58. (Figs. 2, 14 and 16.)

Radially projected from the drum 61 are four releasing fingers 77, 78, 79 and 80 (Figs. 2, 3, 9, 10, 14 and 15), each of said fingers in turn being cooperable with one end 81 of a horizontally disposed lever 82 which is pivoted at 83 to a part of the frame 30, said lever being actuated in one direction by a spring 84 and for cooperation with the end 85 of said lever is a stop 86 forming part of a lever 87 which is pivoted at 88 to a part of the frame 30.

The lever 87 is horizontally inclined and has its free end secured to a pin 89 which is vertically projected from a bolt 90 which is horizontally slidable adjacent its ends in the parts 91 and 92 of the frame 30, and there being a coil spring 93 connected to the part 92 and the lever 87. (Figs. 3, 9, 10 and 11.)

The lever 87 adjacent its free end is provided with an extension 94 which cooperates with the upper end of a vertically disposed lever 95 pivoted at 96 to the frame 30, and said lever adjacent its pivot having a right-angular portion 97 which normally underengages an end part 98 of a locking lever 99, which is pivoted at 100 to a bracket 101, said lever 99 having an undercut recess 102 which normally engages the upper portion of a vertical bottle guiding strip 103 which parallels one side of the slide 32, longitudinally of the bottle loading compartment 31.

The guiding strip 103 has end disposed axes 104, one only being shown in Figs. 9, 10 and 11 and which is supported in a bracket 105 and secured on said axis 104 is one end of an upwardly inclining link 106 and connected to said link is one end of a pull rod 107, slidably in a bearing 107a and having an extending bent part 108 on its opposite end for cooperation with the upper

end of a trip member 109 pivoted at 110 to the swingable frame 67 and said member 109 being cooperable with a stop pin 111 at its lower end. The portion 97 of the lever 95 elevates the end 98 of the lever 99 for releasing the bottle strip 103.

As shown in Figs. 1 and 2 the carton rack 41 is in its lowered position by reason of the counterbalanced bar 42 having the end thereof to which the link 44 is attached, being lowered, said bar being held in this position by the locking part 112 of a shaft 113 to which one end of a spring actuated foot lever 114 is attached, said locking part 112 overengaging a bracket 115 which is fastened to the end 116 of the bar 42. (Figs. 21, 22 and 24.) Also, and as shown in said Figs. 1 and 2, the weight 62 attached to the lower end of the cable 60, was elevated by reason of the cable 60 having been wound on the drum 61 of the windlass 58 by the strap 52 during the descending of the end 116 of the counterbalanced bar 42 by the descending weight of the filled carton A on the rack 41.

In operation

An empty carton A is mounted on the lowered rack 41 and the foot lever 114 is engaged to release the locking part 112 of said lever from engagement with the bracket 115 and the weight 45 of said bar 42 will cause said bar to swing on its pivot mounting 43 as the weighted end thereof descends thereby elevating the end 116 of said bar and the carton rack to the position indicated in Fig. 3 so that the upper end of the carton A will engage the holder 40. (Fig. 4.) In this position the carton is in readiness to receive the full complement of bottles which may have been loaded in the compartment 31.

Release of the trap doors 37 of the bottles loading compartment 31 for discharge of the bottles into the carton

During elevating of the carton rack 41, as it approximately reaches the end of its upward travel a horizontally projected part 117 on said rack will engage a pin 118 projected from a vertically disposed push rod 119, said rod being mounted in guides 120 of the frame 30, and is secured at its lower end to a link 121 which is secured at 122 to a lever 123 which is pivoted at 124 to a part 125 extending from the frame 30, said lever having its free end extending into the lower part of the frame 30 for cooperation with a part 126 extended from the end 116 of the counterbalanced bar 42. (Figs. 1, 3, 21, 26 and 27.)

The upper end of the push rod 119 is connected at 127 to the upper end of a link 128 which is pivoted at 129 to a bracket 130 of the frame 30 and also connected at 127 to the link 128 is a horizontally inclined link 131, said link 131 at its opposite end being pivotally connected at 132 to a horizontal member 133 which extends the approximate length of the loading compartment 31 and is slidably supported in brackets 134 (Figs. 4, 6, 7 and 8), said member 133 having a series of evenly spaced upwardly projecting lugs 135 for cooperation with respective legs 136 which are depended from respective horizontal shaft lengths 137 supported in respective bearings 138 which are secured to and are upwardly extended from a horizontally disposed angle member 139.

Each shaft length 137 is secured to at 140 and extended from an end of a respective trap door 37 of respective bottle stalls 35, the opposite end of each trap door having a shaft length 141

secured to and extending therefrom and being supported in respective bearings 142, said shaft lengths 137 and 141 of each trap door being in axial alignment.

5 Pivoted at 143 to the end wall 144 of the compartment 31 are a series of depending fingers 145 each having a horizontally extending projection 146 on its lower end for underengagement with respective trap doors 37 and in addition each finger has a horizontally projected pin 147 intermediate its length for projecting through respective openings 148 in the end wall 144 of the compartment 31, there being a finger 145 for cooperation with the respective trap doors. (Figs. 4 and 5.)

Owing to the part 126 on the end 116 of the bar 42 engaging the extending end of the lever 123 to which the push rod 119 is attached by the link 121, the horizontal member 133 with which the upper end of the push rod 119 is cooperable by the links 128 and 131, 133 will be held in position whereby the lugs 135 thereof will be in locking engagement against respective legs 136 relating to respective trap doors 37, therefore, the full complement of bottles, if any in the compartment 31, can not be discharged therefrom until the lugs 135 on the horizontal member 133 are disengaged from the legs 136 by sliding actuation of the member 133, effected by the projection 117 of the carton rack 41 engaging the pin 118 of the push rod 119 for actuating the links 128 and 131 to slide the member 133 for disengagement of the lugs 135 from respective legs 136.

Each of the shaft lengths 137 of respective trap doors 37 is provided with a counterweight 149. For swinging the trap doors 37 back into closing position in respect to the compartment 31, after the bottles have been gravity discharged from said compartment, and during while the bottle loaded carton A is descending to a position for discharge from the packer by actuation of the discharging element 47 against the loaded carton and simultaneously with the carton rack 41 reaching the end of its downward travel, the extending end of the lever 123 will be depressed by the part 126 on the end 116 of the bar 42.

This depression of the lever 123 asserts a downward pull on the push rod 119 whereby said rod will return the member 133 bearing the lugs 135 to its locking position by actuation of the links 128 and 131 with which the upper end of the rod 119 is cooperable, thereby holding the lugs 135 in securing abutment against the legs 136 of respective trap doors 37 for holding them in closed positions in readiness for another carton complement of bottles to be loaded into the compartment 31.

Bottle loading of the compartment 31

60 The slide 32 which parallels the loading compartment 31 is of a length to contain six bottles as they are fed from the conveyor 33, said six bottle group to be pushed into the loading compartment 31 by the pusher plate 36, and to prevent bottle jamming or crowding of bottles during the short time period required for the pusher plate 36 to operate, a cut-off blade 150, having its forward end slidable in the vertical bottle guide support 151 actuated by parts borne by the swingable frame 67 of the pusher plate 36 is provided, for insertion between a pair of adjacent bottles of the bottle row. The rear end of the blade 150 is slidably in a slot 152a in a plate 152 borne by the frame 67 and having a notch 153 on its lower edge for cooperation with the lower edge 154 of

said slot and mounted in a bracket 155. Fixed to the frame 30 by a support 156 is a horizontal crank 157 having end disposed crank throws 158 and 159, the crank throw 158 being adapted to engage the lower edge of the blade 150 adjacent the notch 153 thereof and the crank throw 159 extending upwardly for releasable engagement with an opening 160 at one end of a locking strip 161 fixed to the frame 67. (Figs. 2, 17, 18, 19 and 20.)

Assuming that the windlass 58 has been wound or operated whereby the weight 62 is in elevated position and the conveyor 33 has fed a group of six bottles onto the slide 32, the first bottle of the group will engage and push the bolt 90 (Figs. 2, 9, 10 and 11) and as the free end of the lever 87 is mounted on the pin 89 which is projected from said bolt, said lever will move outwardly on its pivot 88 and the stop 86 of said lever will be released from the end 85 of the lever 82 thereby releasing the finger 77 of the drum 61 of the windlass 58 (Figs. 14 and 15) and as said drum is turned in the direction of the arrow 162 shown in Figs. 15 and 16, the shaft 59 of the windlass 58 (Fig. 16) will also turn the drum 57 and the roller 163 on the extending end of the arm 73 which is radially projected from said drum will push against the upper end of the trip lever 69 of the support 68 on the frame 67, thereby swinging said frame on its pivots 66 and the plate 36 of said frame will push the six bottles from the slide 32 into the loading compartment 31 whereby each bottle will be engaged in a respective stall 35 of said compartment.

Simultaneous with the frame 67 swinging forwardly in pushing the six bottle group into the compartment 31, the blade 150 was released from the edge 154 of the plate 152 by the crank throw 159 of the crank 157 being pulled by the locking strip 161 of the frame 67, thus swinging the crank throw 158 upwardly against the rear end of the blade 150 whereby the notch 153 of the blade is disengaged from the edge 154 of the plate 152, and allowing the spring 164 to pull the blade into inserted position between a pair of adjacent bottles of the conveyor fed bottle group.

Also, the lever 87 when moved outward, will cause its extension 94 to swing the lever 95, thus elevating the end part 98 of the lever 99 and releasing the strip 103 from the recess 102 thereof, so that it can fall into sliding alignment with the slide 32.

After the plate 36 of the frame 67 has pushed the entrained bottle row into the compartment 31, it is returned to its neutral position by a retractile spring 165 which is secured at one end to a cross member 166 of the frame 30 and at its other end to the trip lever support 68 of the said frame 67. (Figs. 2, 3 and 14.)

During the bottle pushing operation of the frame 67, upon the finger 77 being released by actuation of the lever 82, the drum 61 of the windlass 58 from which the finger 77 is extended was turned by the weighted pull on the cable 60 a distance whereby the following finger 78 was moved into stopping engagement with the end 81 of said lever. Owing to the retractile spring 93 which is connected at one end to the lever 87 and at its other end to the part 92 of the frame 30, returning said lever to its neutral position as well as the bolt 90, the stop 86 of the lever 87 will hold the lever 82 against being swung by the finger 78 and immediately after the release of the blade 150 from the conveyor bottle row, another

group (second group) of six bottles is fed onto the slide 32.

The first bottle of the second group of six bottles fed onto the slide 32, upon engaging and pushing the bolt 90 will operate the lever 87 to permit release of the finger 78 to allow turning of the windlass 58 so that the roller 163 of the second pusher arm 74 can engage the trip lever 79 of the support 68 to swing the frame 67 and cause the plate 36 to push the bottles of the second bottle row group into respective stalls 35 of the loading compartment 31, said second bottle group engaging and pushing the first bottle group into further position in said loading compartment.

To prevent tipping of the first bottle group as it is being pushed further into the compartment 31 by the second bottle group, a roller 68 is mounted on the lower end of a pair of inclined tracks 168 (Figs. 1, 2, 3 and 4) for holding back engagement with the bottle necks of the first bottle group.

In this illustration of the invention, the carton A is adapted to hold a complement of twenty-four bottles arranged in six bottle rows, therefore, following the loading of the first and second bottle rows into the loading compartment 31, the third bottle row is fed into the slide 32, and subsequently pushed into related stalls of the compartment by the roller 163 of the arm 75 by swinging operation of the frame 67, said arm 75 being projected from the drum 57 of the windlass 58 and bearing against and pushing the trip lever 71 for feeding the third bottle row group into the loading compartment, after the finger 79 of the windlass 58 is released from the lever 85 by actuation of the lever 87 when pushed by the bolt 90.

The loading of the fourth bottle row into the compartment is effected by the roller 163 of the arm 76 of the windlass 58, bearing and pushing against its related trip lever 72 after the finger 80 of the windlass 58 is released from the lever 85 by actuation of the lever 87 and related parts aforesaid.

The feeding of the fourth bottle row into the compartment 31, pushed the preceding third bottle row further into said compartment thereby causing the bottles of the first row to push against the pins 147 of the respective fingers 145 thereby disengaging respective projections 146 from underengagement with respective trap doors 37 after bottle loading the compartment, but the trap doors will not be swung open on account of the lugs 135 of the member 133 being in locked engagement with the legs 136 of respective trap doors.

However, when the rack 41 with the carton A thereon is in elevated position whereby the carton is in proximity with the holder 40 beneath the compartment 31, the rod 119 will have been pushed upwardly by the projection 117 of said rack and the member 133 bearing the lugs 135 will be in unlocked position with respect to the trap doors 37, and the loaded weight of the bottles 65 will open the trap doors as they fall by gravity there-through and into the carton A, due to the projections 146 of the fingers 145 having been released from underengagement with the trap doors.

Immediately upon the bottles falling through the opened trap doors 37 said doors will be swung to closed positions by the respective counterweights 149 on the shafts 137 of said doors, and simultaneously therewith the respective projections 146 of the gravity actuated fingers 145 will

automatically underengage respective doors 37 for holding them in closed positions during while the lugs 135 of the member 133 are released from locking engagement with respective legs 136 of said doors, said lug member 133 also being held in unlocked position by the retractile spring 167 until the loaded carton rack 41 has reached the lower end of its travel whereby the part 126 on the end 116 of the counterbalanced bar 42 will engage and depress the free end of the lever 123 for downwardly pulling the push rod 119 to slide the member 133 for positioning the lugs 135 in locking engagement with respective legs 136 of respective closed trap doors 137. The purpose for the depending gravity actuated fingers 145 is to hold the doors 37 closed for receiving bottles from the slide 32 in the event of a row or more of bottles being pushed into the loading compartment 31, during while the lug member 133 is in retracted position with respect to the legs 136 of said doors.

After each pushing operation of the plate 36 of the swingable frame 67 on each bottle row group, said frame on its return swing will cause the blade 150 to be withdrawn from bottle group separating engagement with the bottle row on the conveyor 33. This is accomplished by the opening 160 of the locking strip 161 borne by the frame 67 overengaging the crank throw 159 of the crank 157, thus returning said crank and its crank throws 158-159 to neutral position whereby the crank throw 158 will permit the rear of the blade 150 to be lowered so that the edge 154 of the plate 152 will be engaged by the notch 153 of said blade, for withdrawing the blade from bottle separating engagement.

After each four bottle row group pushing operation has been accomplished for loading the compartment 31 and/or the carton A with twenty-four bottles, the gravity turned windlass 58 has become unwound with respect to the cable 60 on the drum 61 thereof whereby the weight 62 is in its lowered position, and during while the weight 62 was intermittently descending, the strap 52 was being wound on the drum 57 and the looped end 51 of said strap was consequently raised to its uppermost position in readiness for the pin 49 of the shaft 50 on the end 116 of the counterbalanced bar 42, to be engaged therein against the end or seat 53 of said looped end 51, while the end 116 of the bar 42 is elevated and retained in this position by the weight 45 of said bar overbalancing the rack 41 and the carton A thereon. On the last descending impulse of the weight 62 on the fourth operating cycle of the frame 67 in completing bottle filling of the compartment 31, the bottle filled compartment will overbalance the weight 45 of the bar 42 thereby descending the end 116 of said bar, and the pin 49 of the shaft 50 of said bar will pull the looped end 51 of the strap 52 downward thereby rewinding the cable 60 on the drum 61 of the windlass 58, thus elevating the weight 62 and winding the windlass ready for the next bottle loading of the compartment 31.

As the end 116 of the bar 42 nears the end of its downward swing, and before said end comes to rest on the crossbar 170 of the frame 30 (Figs. 21 and 22), the pin 49 is released from the seat 53 of the looped end 51 of the strap 52 by the pulling effort of the strap on the pin 49 during winding of the cable 60 of the weight 62 on the windlass 58, after the latch 171 on the bar 42 has been disengaged from the leg 172 of the shaft 50, the pulling effort of the strap on the pin 49

rocking said shaft against the tension of the spring 173, connected to the leg 172 and the bar 42, and upwardly inclining the pin 49 to the dotted position shown in Fig. 23, thus releasing 5 said strap from said pin whereby the windlass will be held from operating by the finger 71 of the drum 57 being held in engagement with the end 81 of the lever 82, until released by the next bottle row fed onto the slide 32, in repeated compartment loadings.

Immediately after the pin 49 has been disengaged from the seat 53 of the looped end 51 of the strap 52, the spring 173 of the leg 172 will rock the shaft 50 to its neutral position, and as 15 the end 116 of the bar 42 continues downwardly to rest on the cross bar 170, the pin 49 will be projected into the guideway 174 depending from the looped end 51 of said strap.

During downward swinging of the end 116 of the bar 42, the latch 171 pivoted at 175 to a bracket 176 fastened to the bar 42, is in engagement with the extending end of the leg 172 for preventing the pulling effort of the strap 52 on the pin 49, rocking the shaft 50, whereby the pin 49 would be untimely released from said strap, but as the end 116 of the bar 42 nears the end 25 of its downward travel, the counterbalanced end 171 of said latch will engage the bent part 178 of a post 179, fixed to the cross bar 170 and be 30 rocked thereby for releasing the latch from contact with the leg 172 of the shaft 50, so that said shaft can be rocked for releasing the pin 49 from the strap 52.

On the upward swing of the end 116 of the bar 35 42, the latch 171 will swing by gravity into locking engagement with the leg 172 of the shaft 50 against the stop pin 172a, with the end 177 thereof resting on the pin 180 of the bar 42.

The looped end 51 of the strap 52 is guided by 40 and between a pair of horizontal projections 181 fastened to the bar 42 and an arm 182 horizontally projected from the upper end of a lever 183, pivoted at 184, to a brace 185 of the frame 30, said arm 182 yielding bearing against the guideway 45 174 of the strap 52 by the tension of the spring 186, for maintaining fitting engagement with said guideway and the guideway 187 of said strap which is extended upwardly from the looped end 51 thereof. (Figs. 21 and 23.)

50 When the end 116 of the bar 42 ascends, the shaft 50 is held with the pin 49 horizontally projected therefrom by the latch 171 bearing against the end of the leg 172 of said shaft, therefore, as the pin 49 on being carried upwardly reached the 55 end of the guideway 174 of the strap 52, said pin will be directed into the looped end 51 of said strap and into the guideway 187 thereof by the deflecting strap flange 188, ready for engagement with the seat 53 of the looped end 51, when 60 the end 116 of the bar 42 is swung down by the weight of a bottle filled carton on the rack 41.

Pushing operating cycles of the frame 67 begin 65 upon release of the strap 52 from the pin 49, while the end 116 of the bar 42 is held down by the part 112 of the foot lever 114 engaging the bracket 115, carried by the end 116 of the bar 42, during replacement of a carton on the rack 41 after the loaded carton A has been discharged from the rack by actuation of the element 47 thereagainst.

Upon release of said bar 42 by operating the foot lever 114, the weight 45 of the said bar will 70 swing the end 116 upwardly for positioning the replaced carton on the rack 41 in securance with the holder 40, beneath the loading compartment

31, ready for receiving the bottles loaded into the compartment, while the rack 41 was in lowered position.

After the fourth bottle loading operation of the machine and the end 116 of the bar 42 is swinging down for discharging the bottle filled carton and for replacement of an empty carton on the rack, said bar by the pin 49 will unwind the strap 52 while winding the weight 62 to gravity operating position, and simultaneously therewith, the windlass 58 will be turned to starting position. In this connection retrograde turning of the windlass with respect to the releasing fingers and the pusher arms, each of the fingers 77, 78, 79 and 80 in turn, upon engaging the beveled end 81 of the lever 82, will tilt said lever downwardly on its pivot 83 thereby permitting the fingers to be returned to neutral positions. (Figs. 10 and 15.) The pusher arms 73, 74, 75 and 76 upon being returned to neutral positions will each engage its respective trip lever 69, 70, 71 and 72 and idly swing in on its pivot 189, (Fig. 16).

Each of the trip levers are longer in length below their respective pivots 189 so that they will gravitate to vertically inclining positions against respective stops 190 in the trip lever support 68 of the frame 67, said stops also serving to hold the trip levers in their vertically inclining positions for pushing cooperation with the pusher arms, during loading operations of the frame 67. Upon each return swing of the frame 67, the upper end of the trip member 109 carried thereby will engage and insert a pull on the bent part 108 of the rod 107, to actuate the link 106, for returning the strip 103 to vertical position for locking engagement with the recess 102 of the lever 99.

From the afore description of this improved packaging machine, it is apparent that when the gravity operating weight 62 is uppermost, turning of the windlass 58 thereby is intermittently withheld by the lever 82 engaging and holding respective releasing fingers and their relatable pusher arms. However, the first bottle of each row fed onto the slide 32, upon moving the bolt 90, will in turn cause release of respective fingers from the lever 82, thereby allowing the windlass to function to swing the frame 67 by respective pusher arms engaging relatable trip levers, for pushing respective bottle rows into the loading compartment 31.

Owing to the machine being gravity operated, it is obvious that accident hazard is lessened by reason of the mechanism being counterbalanced, and in consequence, any inadvertent hand protrusion or the like by the operator, would merely stop the mechanism without injury.

What I claim is:

1. A packaging machine for receiving articles to be packaged, comprising a conveyor cooperable to feed the articles in a traveling row into the machine adjacent a loading compartment therein; gravity actuated means for pushing the article row into said compartment; unlocking means for said gravity actuated means, actuated by the leading article of said article row; restoring means for said gravity actuated means; a series of trap doors forming a bottom wall for said compartment; locking means for said trap doors; releasable means for said locking means; a vertically reciprocable rack beneath said compartment having a carton removably mounted thereon for receiving articles discharged from said compartment when the trap doors thereof are opened; means comprising a counterbalanced

bar for reciprocating said rack; and means actuated by said rack for operating the releasable means of said trap door unlocking means.

2. A machine for packaging articles which are conveyor fed in rows thereto; said machine having a receiving compartment with a bottom wall of releasable trap doors and locking means therefor; a carton holding rack vertically reciprocable beneath said compartment; a counterbalanced bar cooperable with said rack; swingable means for pushing the articles in rows into the compartment as they are conveyor fed into the machine; intermittent gravity actuated means impellingly cooperable with said swingable means; releasable means for said gravity actuated means, actuated by the leading article of each article row; restoring means for said gravity actuated means cooperable with said bar; and means cooperable with said rack for unlocking said trap doors for gravity discharge of the articles loaded into said compartment, into the carton on said rack, when said rack is elevated.

3. A machine for packaging articles which are conveyor fed in rows thereto; said machine having a receiving compartment with a bottom wall of releasable trap doors and locking means therefor, a carton holding rack vertically reciprocable beneath said compartment; a counterbalanced bar cooperable with said rack; swingable means for pushing the articles in rows into the compartment as they are conveyor fed into the machine; intermittent gravity actuated rotary means impellingly cooperable with said swingable means; releasable means for said gravity actuated means, actuated by the leading article of each article row; restoring means for said gravity actuated means cooperable with said bar; and means cooperable with said rack for unlocking said trap doors for gravity discharge of the articles loaded into said compartment, into the carton on said rack, when said rack is elevated.

4. A machine for packaging articles which are conveyor fed thereto; said machine having a receiving compartment with a releasable bottom wall of a series of trap doors; a carton holding rack vertically reciprocable beneath said compartment; a counterbalanced bar to which said rack is secured on one end; means for pushing the articles in rows into the compartment as they are conveyor fed into the machine; a gravity actuated windlass having means for intermittent impelling cooperation with said pushing means, actuated by the leading article of each article row; rewinding means for said windlass having detachable connection with said bar; and means cooperable with said rack for releasing the trap doors of said compartment for gravity discharge of the articles loaded into said compartment, into the carton on said rack, when said rack is elevated by said bar.
